UNITED STATES PATENT OFFICE.

JAMES M. DODGE, OF PHILADELPHIA, PENNSYLVANIA, ASSIGNOR TO LINK-BELT COMPANY, OF CHICAGO, ILLINOIS, A CORPORATION OF ILLINOIS.

DESIGN FOR A DRIVE-CHAIN.

41,351.

Specification for Design.

Patented May 2, 1911.

Application filed February 3, 1910. Serial No. 541,939. Term of patent 14 years.

To all whom it may concern:

Be it known that I, JAMES M. DODGE, a citizen of the United States, residing in Philadelphia, Pennsylvania, have invented a certain new, original, and ornamental Design for Drive-Chains, of which the following is a specification, reference being had to the accompanying drawing, forming part thereof.

The figure is a plan view of a drive chain illustrating my design.

I claim:—

The ornamental design for a drive chain as shown.

JAMES M. DODGE.

Witnesses:

Wm. E. SHUPE,

Wm. A. BARR.
